UNITED STATES PATENT OFFICE.

EDWIN S. WILLS, OF PHILADELPHIA, PENNSYLVANIA.

DESIGN FOR GAME-BOARD.

SPECIFICATION forming part of Design No. 34,044, dated February 5, 1901.

Application filed November 21, 1900. Serial No. 7,300. Term of patent 3½ years.

To all whom it may concern:

Be it known that I, EDWIN S. WILLS, a citizen of the United States, residing in the city of Philadelphia, in the State of Pennsylvania, have invented and produced a new and original Design for a Game-Board, of which the following is a specification, reference being had to the accompanying drawings, forming part thereof.

10 The leading feature of my design for a game-board is a series of checker-board blocks circumscribing a blank field at the center thereof.

Figure 1 represents a face view of a game-board embodying my design. Fig. 2 represents a section thereof on line $\alpha\alpha$, Fig. 1.

In the drawings, A designates a board, the same consisting of a series of blocks B B B B of contrasting colors, after the manner of those 20 of a checker-board.

At the center of the board is the square C, which is divested of the blocks B, forming a central blockless field, which is circumscribed by the series of blocks B and breaks said

thus described my invention, what I desire to secure by Letters Patent is

25 a design for a game-board substantially as shown and described.

30 In testimony whereof I have signed my name to this specification in the presence of two subscribing witnesses.

EDWIN S. WILLS.
